GAME

George D. Manville, Los Angeles, Calif.

Application August 29, 1933, Serial No. 687,281

14 Claims. (Cl. 273—142)

This invention relates to games and especially to games of the class involving the use of the conventional playing card comprising full suits of clubs, hearts, diamonds, spades and the "joker".

5 More especially the present game consists of a machine including a spinnable wheel provided with a full deck of playing cards including the "joker," preferably, and means whereby the wheel can be spun and then manually stopped at will 10 in an endeavor to register a desired card of the deck at a given index position.

It is an object to provide a mechanical card game which will be at once entertaining and will be effective in the practice of the eye and coordination of muscular energy by the effort of the player to instantly catch sight of a desired rotating card in the wheel deck and bring it to stop at a desired position.

A further object is to provide a card game 20 machine of rather simple construction, which is thoroughly reliable in its action, which cannot be manipulated in an attempt to make an unfair or cheating play and to provide a machine of compact construction and arrangement of its parts so that while an ample visibility is 25 acquired, the machine will occupy but a reasonably small table or counter plan area so that it can be economically adopted in various classes of public service stores and places of entertainment, 30 and especially it is an object to provide a machine which will be of advertising value because of its inherent attractiveness to the passer-by.

The invention consists in certain advancements in this art as set forth in the ensuing disclosure and having, with the above, additional objects and advantages, and whose construction, combination and details of means, and manner of operation will be made manifest in the description of the herewith illustrative apparatus; it 35 being understood that modifications, variations and adaptations may be resorted to within the scope, principle and spirit of the invention as it is more directly claimed hereinafter.

In this specification and the claims thereof the 40 phrase "deck of playing cards" is intended to mean the physical embodiment in any manner, of the face insignia of the conventional deck of playing cards showing the suits of diamonds, hearts, spades and clubs, and the "joker".

Figure 1 is a perspective of the machine. Figure 2 is an end view of the machine toward the end having an operating crank. Figure 3 is a front view of a broken away portion of the deck wheel chamber of the machine showing a portion 45 of the deck wheel. Figure 4 is a plan of a mount-

ed tally drum. Figure 5 is a sectional plan of the machine with the parts in the normal idle position. Figure 6 is a perspective of the deck wheel spinning mechanism, showing the position in which a wheel impelling dog has been tripped and is in driving mesh with the driving rack-ring 5 of the card wheel and showing a dog releasing device as momentarily held against its tripping abutment.

Figure 7 is a rear elevation of the machine, the back cover of the wheel chamber having been removed and the parts being shown in a normal idle position. Figure 8 is a perspective of the ratchet centering lever which acts upon the deck

10 wheel to bring a card thereof, stopping at a given position, into true register. Figure 9 is a perspective of a wheel governing latch which locks the mechanism in the completion of a predetermined number of actions of the manual crank 15 of the machine. Figure 10 is frontal view of an assembled brake device which stops rotation of the wheel following each play, and which prevents an attempt to unfairly operate the wheel.

Figure 11 is a rear sectional elevation of a ratchet mechanism which provides for a predetermined 20 number of plays, following the inserting of a controlling token and then locks the machine, the parts being shown in a locking position. Figure 12 is a side sectional elevation of the ratchet 25 mechanism of Fig. 11. Figure 13 is a rear elevation of the wheel brake device, shown in the normal, idle, wheel-freeing position. Figure 14 is a rear view of the brake device still in free position, but its tumbler having been thrown to an 30 opposite position (as to Fig. 13). Figure 15 is 35 a rear elevation of the brake device shown in wheel braking position and interrupting an attempted new stroke of a part of the manual crank to prevent cheating.

While the present machine is designed to be 40 initially controlled by the utilization of a token of any desired character, it is to be understood that it may be controlled at will for free manual manipulation if so desired.

In its illustrated embodiment the mechanism 45 of the machine is concealed and protected in a substantial housing including a generally oblong base portion 2 having a front vertical wall 3 intersected by a horizontal, longitudinal step or shelf 4 from which extends upward a large circular chamber 5 having a horizontal axis; the lower portion of the chamber 5 resting on, or merging with, curved pillars or base portions 6.

Fixed on the top of the chamber 5 is a flat 50 panel 7 having one or more window openings in 55

which are presented various playing cards 8, which may be regarded as targets, which the player shall attempt to duplicate by stopping the deck wheel ring 9, Fig. 3, so that the stopped one 5 of its deck of cards 10 will be the same as one of the target cards 8. The deck wheel ring 9 has a plane face on which the deck cards 10 are arranged in a plane ring, each card being of a size to correspond to a face window 11 at the top 10 of the chamber 5 and just below the target panel 7.

When the machine is of the token controlled adaptation, the player drops the requisite token into the token aperture 12; in the present instance being shown just below the deck card 15 window 11.

A feature of the invention resides in means whereby the play made by an individual player; that is whatever card is stopped in the window 11, can be made of record and a tally 20 kept of his or her series of plays. For this purpose the step 4 of the housing is provided with a suitable number of windows 13; two groups of such windows here being disposed, one on each side of the medial transverse line of the step 4 so 25 that two players may make up a game as follows:

One player say choosing the left-hand set of windows 13 turns each of his series of knobs 14, in the front panel 3 and by so doing turns a tally or choice drum 15, Fig. 4, so as to bring a playing card symbol 16 to registered position with its respective window 13. Each drum 15 has its periphery provided with a full deck of card symbols 16 of the four suits and the "joker" and it is therefore possible for one player to manually 30 present any card symbol 16 of a whole deck as he may desire at his group of windows 13. Then it shall be the object of the other player choosing the right-hand set of windows 13 to spin the deck wheel 9 and then stop it so that he will register a card of the deck 10 at the window 11 which 35 will correspond to one of the match symbols 16 set by the player on the left-hand group of windows 13. Obviously, if the player can spin the wheel and match the choice set up at the left-hand group of windows, he will make a score. 40 The drums 15 are fixed on the shafts of the knobs 14 and the drums are frictionally held by a spring friction device 17, Fig. 4.

For the purpose of spinning the deck wheel 9 there is provided on the right-hand end of the machine a hand crank 18 fixed on a shaft 19, Fig. 7, mounted in bearings 20 and 21 and having a stop lug 22 engaging a flange 23 to limit the rotation of the crankshaft 19 to about a quarter 45 of a turn when the player pulls the crank 18 forward from the normal vertical position, Fig. 2. The handle is pulled to its normal rest position by a substantial spring 24 one end of which is anchored to a fixed part and the other end connected to a lever 25 fixed on the shaft 19.

Fixed on the inner end of the crank-shaft 19 is a bevel gear 26 in constant mesh with a like bevel gear 27, which is fixed on counter-shaft 28 mounted in suitable bearings one of which is carried by 50 an inverted U-frame 29 suitably fixed to the wall of the chamber 5. Rigidly fixed on the shaft 28 is a radial arm 30 from the hub of which extends a leg 31 having a pair of angularly spaced, co-planar feet 32-33 provided for the purpose of actuating a wheel brake device later described.

The outer end of the arm 30 is slightly forwardly offset at 30^a, Fig. 6, and adjacent the offset there is provided a wedge finger 30^b beyond which the arm has a pivot 34 on which is mounted a trigger 35 including a hook portion 36. Extend-

ing oppositely from the trigger 35 is a tripping cheek 37 which is designed to engage a tripping abutment 38 fixed to the upper portion of the chamber 5, Fig. 7. The trigger 35 is normally retracted by a light spring 39, one end of which is anchored to the lever arm 30, this latter having a shoulder 30^c limiting inward pull of the member 35.

The latch 35, when in a position of rest, Fig. 7, is in opposition to a slide or dog 40 resting on a ledge 41 of the chamber 5 and carrying a free latch 42 whose inner, lower end is designed to engage with a toothed, spinning ring 43 forming a part of the deck wheel and being rigidly connected to its deck ring 9 so that these parts rotate as one.

When the player pulls forward the handle 18, the shaft 28 is turned and the lever arm 30 starts an upward movement which causes the hook 35 of the trigger to engage the spur 40^a of the dog 40 and this is lifted upwardly along a fixed curved bar 44 extending from the ledge 41 over to an opposite ledge 41^a. Surrounding the curved bar 44, this being concentric to the shaft 28, is a coiled spring 45 resting at one end on the top of the dog or slide 40 and at its opposite end on the ledge 41^a so that as the dog 40 is pulled upward by the lever arm 30 under manual operation the spring 45 is compressed and energized. When the upwardly moving arm 30 carries the trigger 35 cheek 37 against the tripping abutment 38 the latch 35 releases the dog 40 by disengagement from the spur 40^a and therefore the spring 45 instantly acts to drive the sliding dog 40 down the curved supporting bar 44. During the normal idle position of the arm 30 and the dog 40 the finger 30^b of the arm is lying in a wedge position between the dog 40 and the top of the latch 42 so that the point of the latter is held clear of the teeth of the impelling ring 43, as shown in Fig. 7. This position is maintained while the lever arm 30 is moving upward and until the trigger 35 is tripped by the abutment 38 immediately following which the latch or pawl 42 drops into an impelling engagement with the ratchet ring 43. The teeth of the ring are formed at irregular distances so as to aid in accomplishing an indeterminate wheel action.

The rear face of the wheel ring 9 is provided with an annular shoulder 9^a adapted to be engaged by a brake segment 46, Fig. 10, attached to a standard 47 having a rearwardly turned head 48 perforated to receive and slide on a fixed post 49 at the bottom of the chamber 5, Fig. 7. The standard also has guide pins 50 operating through aperture provided therefor in the bottom of the chamber wall. Surrounding the post 49 is an expansion spring 51 acting to thrust the brake 46 upward when so permitted. Fixed to the front face, Fig. 10, of the standard 47 is a stop lug 47^a extending into the recessed top of a tumbler 52 of triangular form and which is pivoted at 53 on the lower portion of the standard 47. Fixed to the front face of the tumbler 52 is a horn 54 which is out of the plane of the tumbler, this latter being in the plane of the stop lug 47^a so that as the tumbler rocks from side to side on its pivot 53 its motion is limited by the stop lug 47^a.

When the machine is in the normal idle position, Fig. 7, the brake lug 47^a is being engaged by the lowermost, innermost toe end of the foot part 32 above referred to and this being a part of the operating arm 19. The toe of the foot 32 is pressing the brake downward against the uplifting action of its spring 51. At the instant of clock-

wise rotation of the arm 19 and foot 32 the latter moves from the brake lug 47^a, Fig. 10, and the brake 46 is pressed upward into holding engagement with the shoulder 9^a of the deck ring 9. 5 The brake remains applied until the toe 33^a of foot 33 moves around and engages the top of the brake lug 47 so that the latter is depressed to release the deck wheel at substantially the same instant at which the dog trigger 35 engages the fixed abutment 38 thus freeing the wheel just as the dog pawl 42, Fig. 6, drops into driving engagement with the ratchet ring 43 which accomplishes the spinning of the wheel under the expanding impulse of the motor spring 45. 10

15 The brake is shown in thrown-off position in Fig. 13 and in Fig. 14 it is also shown in thrown-off position by the action just above described, of the toe 33^a of the foot 33; in both cases the brake lug 47^a being engaged and pressed down by first the foot 32 and then the foot 33. Means are provided to prevent a re-pull of the manual hand-crank 18 just following the spinning action of the dog pawl 42 on the wheel and this includes a stop shoulder 33^b, Fig. 15, which is designed to move over against the upper contiguous corner 52^a of the tumbler 52 so that an unfair player cannot work the wheel in an attempt to make a cheating play. The tumbler 52 is thrown from one position to another on its pivot 53 on the brake standard 47 by means of a pin 32^a, Fig. 13, which engages the horn 54 when the foot moves anticlockwise to its normal position of rest, Fig. 13. When the manual crank 18 is pulled forward the foot 33 starts down toward the tumbler and has a tumbler pin 33^c, Fig. 14, which on engaging the tumbler at position, Fig. 13, throws it over to positions of Figs. 14 and 15. 20 It will be noted that the toe 33^a of the foot 33 in Fig. 15 is clear or free of the brake lug 47^a so that the brake spring 51 acts to automatically apply the brake to the wheel and stop it. 25

30 Means are provided to regulate the number of wheel actions or spins which may be had following the insertion of a proper token into the token hole 12, Fig. 1. In the present case this means includes a disc or cylinder 56 fixed on the counter-shaft 28 and being provided with a snap bolt or ratchet pawl 57 pressed into engagement with the internal surface ratchet rotor 58 suitably, turnably mounted as to the shaft 28. The inner face of the rotor is provided with a series of ratchet teeth 59 to be successively engaged by the ratchet pawl 57 as this oscillates the requisite degree in consonance with oscillations of the shaft 28 by its operating crank 18. The ratchet rotor 58 is normally under the frictional drag of a brake 60 so that while the rotor can be turned clockwise in Fig. 11 with the ratchet cylinder 56 the brake prevents the return of the rotor with the ratchet device; it being borne in mind that Figs. 7 and 11 are rear elevational views. At commencement of operation of a series of ratchet movements the cylinder 56 and its associate rotor 58 are simultaneously held locked by a locking detent 61 having a flange 62 adapted to snap into detent notches 63 and 64 respectively in the rotor 58 and the ratchet cylinder 56, Fig. 12. 35

40 When the proper token has been deposited it will lodge between a shoulder 61^a of the detent 61 and a push bar 56^a, Fig. 12, fixed on the outer face of the ratchet cylinder 56. Hence, when the cylinder 56 is turned in the direction of the arrow, Fig. 11, the token T reacts against the detent 61 and swings this outward on its pivot 65 and re- 45 moves its flange 62 from the notches 63—64 thus allowing the cylinder 56 and its ratchet pawl 57 to interlock with the contiguous tooth 59 of the rotor 58 and the latter is turned one ratchet pitch under crank effort. The coin escapes from its effective position to a money box M in the bottom of the housing. When the locking detent 61 has been released from action of the token T its spring 66 pulls the detent flange 62 back on to the even perimeters of the cylinder 56 and rotor 58 in which position it will ride until the rotor 58 has made one complete revolution in successive steps of ratchet action whereupon the detent flange 62 will snap into locking position in the presented notches 63—64 of the parts and it will then take the presence of another token to start a fresh series of ratchet impulses on the rotor 58. 50

55 The cylinder 56 is provided with a perimetral nog 67, Figs. 7 and 11 and in the idle position of the parts this nog is repressing a hook 68 clear of a shoulder 69 fixed on a swinging lever 70, which has a downwardly projecting portion carrying a block 71 presenting an angular corner toward and engageable in a series of notches 72 formed internally on the deck ring 9, Figs. 3 and 7. A spring 73 normally exerts a pulling action on the lever 70 with the result of pressing a centering block 71 into such one of the ring notches 72 as may be adjacent to the block 71. The ratchet cylinder 56 is further provided with a nog 74 and this operates on its upward movement toward the shoulder 69 of the lever 70 to swing this lever upward on its pivot 70^a, Fig. 8, until the shoulder 69 is grappled by the hook 68 which then is in a receiving position since the nog 67 moves upward and away from the hook 68 coincident with the upward movement of the lug 74. It will be seen that the centering device is retracted from the wheel prior to and during the spinning movement of the wheel and as the nog 67 again moves down and engages the hook 68 the centering device is released and becomes effective to snap against the contiguous notch surface 72 with such pressure as to be effective to slightly shift the wheel to accurately register a card of the wheel deck at the index and display window 11, Fig. 1. 55

60 It is understood that the wheel brake 46 is thrown off shortly following the tripping of the centering device by the nog 67 and just as soon as the brake is off the pressure of the tripped centering device is sufficient to center the wheel. The centering notches 72 are equal in number to the number of cards provided on the face of the deck wheel. 65

65 From the above it will be seen that the operator pulls the handle 18 forwardly to energize the spinning spring 45 and effects the tripping of the dog trigger and the release of the dog at the conclusion of the forward pull of the crank. As the handle is moved backward under pull of its spring 24 but while still in control of the operator the lever 30 moves down to again bring the trigger to latching position with the dog and incidentally move the centering control lug 67 against the release hook 68 and bring about the release of the centering device 70—71 and at the same time swing the feet 32—33 back to normal position and tip the tumbler 52 to the normal position of Fig. 13. Meanwhile during the return of the handle or crank the wheel has started its spinning movement and at the instant that the toe 33^a of the foot 33, Fig. 14, moves enough to release the brake lug 47^a the brake automatically sets on the shoulder 9^a of the deck wheel and the latter is stopped. The player may hold the crank forward as long as he desires during the spinning of the wheel and 70

70

75

as this slows down he will endeavor to stop one of the deck cards at the register window 11 which will duplicate one of the cards in the target panel 8, or if he desires, he may try to match one of the 5 series of card symbols shown at the left-hand group of windows 13 in the bench 4 of the housing. As before explained the foot 33 is provided with a back-stop 33^b, Fig. 15, to prevent unfair movement of the mechanism during its play.

10 When the detent 61 is thrust outward by action of an inserted token T it acts through a U-shaped lever 75 to actuate a token counter 76 suitably fixed in the machine.

15 Various forms of games may be devised to play on the machine and a player setting up a group of cards at the windows 13 of the left-hand group will be outplayed by a player operating the card wheel 9 in such a skillful manner as to stop a better hand or series of cards and tallies at the 20 right-hand group of windows 13. It will be seen that skillful players in the spinning of the wheel can operate the wheel to match the target cards 8 or to match the opponent's selected hand or to better it.

25 What is claimed is:

1. A rotative carrier having a fixed deck of playing cards, an index at which the cards of the deck may be individually halted, a hand crank, a mechanism for spinning the deck carrier, an operative connection between said crank and said mechanism and an automatic brake device controlled by said crank to release the carrier for spinning action and to permit the brake to act, at the player's will, to stop the wheel and a centering device for registering a halted card with the index and means, controlled by the crank, to release the brake to permit centering action of said device.

2. A rotative carrier having a fixed deck of playing cards, an index at which the cards of the deck may be individually halted, a hand crank, a mechanism for spinning the deck carrier, an operative connection between said crank and said mechanism, and an automatic brake device controlled by said crank to release the carrier for spinning action and to permit the brake to act, at the player's will, to stop the wheel and a centering device for registering a halted card with the index and means, controlled by the crank, to release the brake to permit centering action of said device, and to prevent a partial re-pull spinning action of the crank.

3. A rotative carrier having a fixed deck of playing cards, a spring motor for spinning the carrier, a hand crank for energizing the motor, means to automatically trip the motor for spinning the carrier, an automatic brake to stop the carrier under crank control, means providing for a predetermined number of spins of the carrier and including means to lock the carrier after its predetermined number of spins.

4. A rotative carrier having a fixed deck of playing cards, a spring motor for spinning the carrier, a hand crank for energizing the motor, means to automatically trip the motor for spinning the carrier, an automatic brake to stop the carrier under crank control, and means to permit a predetermined number of spins of the carrier and then lock it; said means including a cylinder and a ratchet rotor, and a detent for locking the rotor and the cylinder subsequent to a given number of spins.

5. A rotative carrier having a fixed deck of playing cards, a spring motor for spinning the carrier, a hand crank for energizing the motor,

means to automatically trip the motor for spinning the carrier, an automatic brake to stop the carrier under crank control, and means to permit a predetermined number of spins of the carrier and then lock it; said means including a cylinder and a ratchet rotor, and a detent for locking the rotor and the cylinder subsequent to a given number of spins, and token controlled means for operatively connecting said rotor and said detent to unlock the rotor and the cylinder.

6. In a machine of the class described, a crank, a wheel consisting of a plane, card deck ring part and a ratchet ring part, a shaft on which the wheel is freely turnable, an arc bar fixed concentric to said shaft and a spring coiled about said bar, a sliding dog on said bar having a pawl to engage said ratchet ring, means operatively connecting said crank and said shaft, an arm fixed to said shaft and having a trigger to pick up said dog and move it to compress the spring and to automatically release the dog for spring impulse on said ratchet ring, a normally free brake operative on said wheel to stop it, and means fixed on the shaft to release the brake for action on the wheel and to throw the brake off in sequential actions.

7. In a machine of the class described, a crank, a wheel consisting of a plane, card deck ring part and a ratchet ring part, a shaft on which the wheel is freely turnable, an arc bar fixed concentric to said shaft and a spring coiled about said bar, a sliding dog on said bar having a pawl to engage said ratchet ring, means operatively connecting said crank and said shaft, an arm fixed to said shaft and having a trigger to pick up said dog and move it to compress the spring and to automatically release the dog for spring impulse on said ratchet ring, a normally free brake operative on said wheel to stop it, and means fixed on the shaft to release the brake for action on the wheel and to throw the brake off in sequential actions and means for centering a card of the ring deck at an index when the brake is off.

8. A game case having a front bench portion from which extends upward a vertical face; said bench having a series of top windows and its front face having a row of knobs aligned to respective windows on the top, and a series of indicators below the windows and operative by relative knobs of the row.

9. In a machine of the class described; a wheel consisting of a circular indicia member having a cylindrical periphery for brake application, an annular toothed part for a centering action of a cooperative device, and an asymmetrical circular rack for action of an impelling means.

10. In a machine of the class described; a freely rotative wheel provided with a ratchet-toothed annulus, and an impelling means therefor including a setting lever, a main spring coiled on an arc-bar, a ratchet slidable on the bar by said lever to energize the spring, and means to free the ratchet from the lever and permit its impulse by the spring and reaction on the ratchet annulus.

11. In a machine of the class described; a freely rotative wheel provided with a ratchet-toothed annulus, and an impelling means therefor including a setting lever, a main spring coiled on an arc-bar, a ratchet slidable on the bar by said lever to energize the spring, and means to free the ratchet from the lever and permit its impulse by the spring and reaction on the ratchet annulus; and brake means controlled by the lever to stop the wheel at will.

12. In a machine of the class described; a freely rotative wheel provided with a ratchet-toothed annulus, and an impelling means therefor including a setting lever, a main spring coiled on an arc-bar, a ratchet slideable on the bar by said lever to energize the spring, and means to free the ratchet from the lever and permit its impulse by the spring and reaction on the ratchet annulus; and brake means controlled by the lever to stop the wheel at will; the wheel having a toothed centering annulus, a centering means coacting with the centering annulus, and means to effect the brake release to permit the centering action on the stopped wheel.

15. 13. A spinnable wheel, a main spring for spin-

ning the wheel, a brake for stopping the wheel at will, a centering device for registering the wheel as to an index, and a single lever for energizing the spring, for effecting the setting of the brake and for momentarily releasing it while the centering device functions.

14. In a game machine, a vertical, mechanism casing provided with a basal portion which includes a frontal bench with a plane top having a longitudinal row of windows for showing subjacent elements, and the bench having a front, vertical wall provided with a set of knobs for operation of the said elements.

GEORGE D. MANVILLE. 15
